Gardner Chilson, of Boston, Mass.
Letters Patent No. 1248, dated June 12, 1860.

The schedule referred to in these ^{Drawings} Letters Patent and making part of the same,
To all persons to whom these presents shall come.

Be it known that I, Gardner Chilson,
of Boston, in the County of Suffolk, and State of Massachusetts have invented or in -
duced a new or improved Ornamental design or configuration for a Cooking Range the
same being represented in the accompanying drawing which is a perspective view of
the said range as set in brickwork and furnished with the usual boiling vessels ap -
plied to the cap plate of the furnace.

The design in question includes the panelled doors and the front

or door frame of the oven, the panelled tapering flue (leading from the fire place to the oven flues) and the front frame of the furnace with its ornamental mouldings, panels, and panelled doors or covers.

In the drawings A, is the oven door frame, while B.B.B.B. are its panelled doors; C. is the tapering flue, while D. is the furnace frame which is made with rosetted panels, a. a. on its front and also a rosetted panel b. on each end, each panel having the form and being made with rosettes or a tapering projection as shown in the drawing.

E and F. are the panelled covers of the furnace or grate while G. is the ash pit register cover. Each of the parts E, F. is panelled and provided with rosettes in each panel. The cap plate is furnished with a double twist or rope moulding along its edge.

I claim the design for the cast metal front of the range, as formed and ornamented with rosetted panels and mouldings or other ornamental characteristics as shown in the said drawing, and

I also claim as part of such design the panel formed with mouldings and the rosettes arranged on a tapering projection.
